DESIGN FOR A FURNITURE DRAWER

Jacob C. Garver, Tippecanoe City, Ohio, assignor to Detroit Cabinet Company, Inc., Tippecanoe
City, Ohio, a corporation of Ohio

Application December 29, 1933, Serial No. 50,249

Term of patent 3½ years

To all whom it may concern:

Be it known that I, JACOB C. GARVER, a citizen of the United States, residing at Tippecanoe City, in the county of Miami, and State of Ohio, have invented a new, original and ornamental Design for a Furniture Drawer, of which the following is a specification, reference being had to the accompanying drawing forming a part thereof.

In the drawing: Figure 1 is a front elevation of a furniture drawer, showing my new design.

I claim:

The ornamental design for a furniture drawer substantially as shown.

JACOB C. GARVER.
